UNITED STATES PATENT OFFICE.

LOUIS H. SCHECK, OF BATAVIA, NEW YORK.

ICE-CREAM CAN.

939,865.

Specification of Letters Patent. Patented Nov. 9, 1909.

Application filed May 27, 1908. Serial No. 498,615.

To all whom it may concern:

Be it known that I, LOUIS H. SCHECK, a citizen of the United States, residing at Batavia, in the county of Genesee and State of New York, have invented certain new and useful Improvements in Ice-Cream Cans, of which the following is a specification, reference being had to the accompanying drawings.

10 This invention relates to improvements in ice cream cans and more particularly packing cans used at soda fountains and similar places for holding different kinds of ice cream and the like.

15 One object of the invention is to provide an improved duplex can in which two different kinds of ice cream may be kept in a single ice-box or holder.

Another object of the invention is to provide 20 improved means for retaining the can in the usual perforated ice spacing cylinder or jacket and retaining the latter in the ice.

With the above and other objects in view, the invention consists of the novel features 25 of construction and the combination and arrangement of parts hereinafter fully described and claimed, and illustrated in the accompanying drawings, in which—

Figure 1 is a plan view of an ice-box showing 30 my improved duplex can therein, with its cover removed; Fig. 2 is a perspective view of the spacing jacket showing the can sections secured therein and also showing the cover spaced slightly above the can; Fig. 3 is a vertical section through the same; Fig. 4 is a perspective view of one of the 35 can sections; and Figs. 5 and 6 are perspective views of the two locking devices, one of which is adapted to serve as a disher 40 scraper.

In the drawings 1 denotes an ice-box or chest containing ice and salt 2 within which my improved packing can for ice cream or the like is arranged. In the present embodiment of the invention my can consists of two 45 half sections 3 each of which is of substantially semi-cylindrical form having their flat faces opposed to and in contact with each other, but it will be understood that three, four or more can sections may be employed 50 instead of only two as shown in the drawings. These can sections are arranged in a perforated jacket 4 of substantially cylindrical form which serves to space the ice 55 from contact with the can sections 3 so that they may be readily removed and replaced

without removing the ice. To retain the jacket or cylinder 4 in the ice, stop projections or arms 5 are provided on its outer surface to be attached to a frame in the ice 60 box and thereby anchor it. These stop arms 5 are preferably in the form of angle plates riveted or otherwise secured to the jacket at intervals around its lower portion.

For the purpose of retaining the can sections 3 within the jacket or cylinder 4 and prevent them from floating in the salt water which surrounds them, I provide two removable and adjustable locking devices 6, 7, 65 on the opposite sides of the upper portion 70 of the jacket 4 for engagement with said can sections. These devices are similar in construction each being formed from a metal strip bent upon itself at its upper end to form a hook 8 which has two prongs 9 to enter the can sections 3 on opposite sides of their straight contacting inner walls. If desired, the hook portion of the device 7 may be made comparatively broad as shown 75 at 10, and bent at an angle of 45° so that 80 said device, when in position in the jacket 4, may be used as a scraper to scrape ice cream from a disher scoop or similar device. By constructing the device in this manner it 85 serves both as a lock for the cans and as a 90 stationary scraper blade across which the ice cream disher may be drawn to level the disher or scoop and thereby prevent waste or over-measure. The ice cream removed by the scraper blade falls back into the cans. 95 The lower ends or shanks 11 of the devices 6, 7 are slotted longitudinally as shown at 12 to receive clamping bolts 13 arranged in apertures in the jacket 4 and having thumb nuts 14 on their outer threaded ends. The 100 lower portions of the shanks 11 are curved longitudinally so that when the bolts are loosened and the device pulled upwardly their hook shaped upper ends will be swung upwardly and outwardly away from the can sections.

15 denotes a cover shaped to fit over the jacket 4 and having a depending surrounding flange 16 to receive the open top of the perforated jacket 4. The opposite sides of 105 the flange 16 have offset portions 18 to receive the locking devices 6, 7, as clearly shown in the drawings. This cover must be used on the cans when the ice-box is packed with ice in order to prevent salt and water 110 from entering the can sections.

From the foregoing it will be seen that the

invention provides a simple and practical ice cream packing can especially adapted for use at soda fountains and ice cream saloons and the like, where it is necessary to keep 5 different kinds or flavors of ice cream and ices. The use of the invention will effect a saving both in salt and ice and also an economy in space since two or more kinds of ice cream may be kept in a single ice-box.

10 Having thus described the invention, what is claimed is:

1. The combination of a can, a spacing jacket to receive the same, a can-retaining member having a shank secured to the jacket, 15 and a hook-shaped upper end to take over the upper edge of the can, said hook-shaped upper end of the member having its portion within the can enlarged to form a scraper blade.

20 2. The combination of a foraminous spacing jacket, can sections arranged in said jacket, and a locking device upon the jacket and adapted to take over the upper edges of

both of the can sections to retain them in the jacket.

25 3. The combination of a foraminous spacing jacket, can sections arranged in said jacket, and a locking device adjustably mounted on the jacket and having spaced hook-shaped portions to take over the upper 30 edges of both of the can sections to retain them in the jacket.

4. The combination of a foraminous spacing jacket, can sections arranged in said jacket, a locking device having a shank 35 mounted on the jacket and having spaced hook-shaped portions to take over the upper edges of both of the can sections, said hook-shaped portions having broad flat plates to form scraper blades.

40 In testimony whereof I hereunto affix my signature in the presence of two witnesses.

LOUIS H. SCHECK.
